UNITED STATES PATENT OFFICE.

ARTHUR E. MILLIES, OF MILWAUKEE, WISCONSIN.

ANCHOR FOR SAFETY HARNESS.

Application filed May 3, 1921. Serial No. 466,568.

To all whom it may concern:

Be it known that I, ARTHUR E. MILLIES, a citizen of the United States, residing at Milwaukee, county of Milwaukee, and State 5 of Wisconsin, have invented new and useful Improvements in Anchors for Safety Harness, of which the following is a specification.

This invention relates to improvements 10 in anchors for the safety harness of window cleaners.

It is the object of this invention to provide an anchor which may be securely embedded in a wooden structure either at the 15 time the structure is being erected or after it is complete without marring the surfaces of the woodwork.

It is a further object of this invention to provide an anchor which may be embedded 20 in the window frame of any structure and which when so embedded may be secured beyond the possibility of accidental removal. More specifically, it is the object of this invention to provide an anchor having 25 an angularly disposed tang adapted to be driven with a close fit into a hole which may be bored to receive it in any wooden structure and which will cooperate with other securing means and with a base plate 30 to make any accidental movement or removal of the anchor impossible.

A further object of this invention is to provide an anchor with a safety retaining device capable of holding the anchor in 35 place, even tho the screw which normally secures the anchor to the building has been removed.

In the drawings:—

Figure 1 is a fragmental elevation of a 40 window casing of which a portion is broken away to expose an anchor embodying this invention.

Figure 2 is a perspective view of the 45 anchor on a larger scale, showing it provided with the special retaining device with which it may be equipped if desired.

Figure 3 is a detail view of the end of the 50 tang, the tang being cut away upon a section exposing the securing device herein-after to be described.

Figure 4 is a detail view showing an anchor having a modified form of retaining device applied to a wooden structure.

Like parts are identified by the same reference characters throughout the several views.

It will be understood that a device embody-

ing this invention is particularly adapted to be secured to a wooden structure, and may be used in any part of a wooden structure to perform any function for which it is suited. Anchors used for this purpose, however, are ordinarily associated with a window frame so that when the window cleaner stands upon the sill to wash the outside of the window, he may fasten his safety 65 harness to one anchor upon each side of the frame.

In Figure 1 is shown at 10, a portion of the window frame, the upper sash being illustrated at 11 and the lower sash at 12. 70 The body of the anchor is made in the form of a plate 14 which has a plane surface adapted to contact with the window frame. The outer surface 15 may be rounded or beveled at the corners if desired to improve the appearance of the device. Mounted upon the surface 15 and preferably made integral with the plate 14 is a T-shaped block 16 over which a fastening device carried by the safety harness of the window 75 cleaner is adapted to be secured in the usual manner. An opening 17 in plate 14 is adapted to receive a screw 18 which may be turned into the window frame with which the device is associated. At the back of plate 14 is 80 the tang 20 which projects downwardly therefrom at an angle. Tang 20 is to be driven to an exceedingly close fit in the hole prepared to receive it. This tang is also 85 preferably made integral with the base plate 14.

The point at which the tang is attached to the plate is preferably adjacent to the base of the T-shaped block 16, thereby causing the centers of turning moments in all 90 planes to coincide substantially at this point. In this way the various elements of the anchor are enabled to co-operate with each other to the fullest possible degree in resisting any force tending to displace the anchor. Whether the strain is upward, downward, or sideward, the tang will immediately tend to cramp in the hole into which it is driven and the plane portion of the plate 14 will press with added force against 100 the wooden surface upon which it bears. Screw 18 in addition to its obvious function of securing the tang against withdrawal, also serves to maintain the plate 14 closely pressed against the wooden surface to prevent any possible destructive play or movement of the anchor, which might 110

result in loosening the tang in the recess made to receive it.

It will be noted that the tang 20 has a diameter of less length than the width of block 14 so that the rear or plane surface of said block forms a shoulder upon each side of tang 20 thereby providing a bearing surface adapted to aid in taking up side strains upon the anchor. By reason of the fact that the tang 20 is set at a decided downward angle the greatest strains upon the anchor occur in a vertical plane. For this reason, the bearing block 14 is extended above and below the tang to give extended bearing surfaces upon the window casing in this plane.

The anchor as above described will be found amply secure for ordinary service; but where additional safety is necessary the special retaining device shown in Figures 2 and 3 may be incorporated. The tang 20 is prepared to receive this retaining device by boring a transverse hole 6 and constructing the recesses 7 at each side of the tang, communicating therewith. A piece of spring wire 8 bent into the shape of a letter U comprises the safety device adapted to be inserted into the hole 6 and recesses 7. If desired the tips of the wire may be bent slightly outwardly as at 9 to facilitate their entry into the wood if the withdrawal of the anchor is attempted.

It will be understood that while the tang is being driven into the wood the spring wire will be forced into the recesses 7; but if the tang is withdrawn from the wood the bent ends 9 of the wire 8 will be urged by the flexion of the wire and by the movement of the tang to penetrate deeper and deeper into the wood. Experiments have demonstrated that even without the screw 18 in place an anchor equipped with the safety wire 8 can with difficulty be extracted with a pinch bar. Therefore an anchor made in accordance with this invention would remain operative to save life in spite of a mischievous or criminal attempt to tamper with it. The safety device, once the anchor is installed, is inaccessible to the elements as well as to malicious individuals.

In the modified form of anchor shown in Figure 4, the base plate 14, the block 16, screw 18, and tang 20 correspond to the anchor already described, except that the tang 20 is provided near its lower end with a hole 21 bored normal to the inner plane surface of the base plate 14. In boring the hole 22 adapted to receive tang 20, a jig or other well known device may be used to direct the bit. If a jig is used, it may also provide means for indicating the position and direction of the hole 23 which is adapted to register with the hole 21 in tang 20 and to receive the pin 24. This pin 24 is driven into place after the anchor has been posi-

tioned as shown and interlocks with the tang 20 to prevent absolutely the withdrawal of the anchor. If desired, the pin 24 may be driven out of sight into the member 10 and the opening through which it entered may be puttied up to conceal the existence of the pin. The use of pin 24 or of the spring wire device hitherto described is optional, as for all ordinary purposes the anchor is unusually secure even without these additional interlocking devices.

The operation and use of the anchor has been described incidental to the foregoing discussion of its mechanical characteristics, but a brief summary thereof will be given:

By means of a jig or other suitable device, the hole 22 is bored into the window casing at the proper angle to receive the tang 20. The hole is preferably made to receive the tang with a driving fit so that when the tang is driven into the hole, it will be rigidly anchored therein. The anchor is now driven home to the position in which it is shown in Figures 1 and 4 with the tang seated deep in the frame of the window and the plate 14 flush with the exterior surface of the frame. The screw 18 may then be turned up through hole 17 into the wood of frame member 10 and if the device shown in Figure 4 is being used, the pin 24 may be inserted to interlock with the inner end of tang 20. It will be obvious that with the device so secured to the frame member 10, movement in any direction is impossible. Tang 20 will cooperate with the broad, flat surface of plate 14 and with the retaining screw 18 to resist movement in any direction whatsoever. The fact that the tang 20 and the screw 18 enter the frame member at an angle to each other provides ample security against the accidental withdrawal of the anchor. For special cases where additional security is desired, the spring wire 8 or pin 24 may be used. Either of these devices will serve to retain the anchor in place tho the screw 18 be removed, and either will prove inaccessible.

I claim:

1. The combination with a window frame provided with an inclined recess, of a tang disposed in said recess, an apertured plate attached thereto, and a screw passing through said plate and into said frame on an axial line angularly deviating from the axis of the tang.

2. The combination with a window frame provided with an inclined recess, of a tang disposed in said recess, and provided with grooves upon opposite sides thereof and joined by a transverse bore, an anchoring member passing through said bore and bent to lie within said grooves and extending toward the outer end of said tang, a plate integral with said tang and apertured at a point remote therefrom, and a screw passing

through said aperture and into said frame on an axial line angularly deviating from the axis of the tang.

3. An anchor for safety harnesses adapted to be secured to a window casing having an inclined recess, said anchor including a tang adapted to be inserted in said recess and an apertured plate attached to said tang, the

aperture in said plate having its axis on a line angularly deviated from the axis of the tang, whereby a screw may be passed through said aperture and into said window frame at an angle angularly deviated from the tang.

ARTHUR E. MILLIES.
